SEBASTIAN OEDAMER, OF MUSCATINE, IOWA.

Letters Patent No. 89,234, dated April 20, 1869.

IMPROVED WASHING-MACHINE.

The Schedule referred to in these Letters Patent and making part of the same.

To all whom it may concern:

Be it known that I, SEBASTIAN OEDAMER, of Muscatine, in the county of Muscatine, and State of Iowa, have invented a new and useful Improvement in Washing-Machines; and I do hereby declare that the following is a full and exact description thereof, reference being had to the accompanying drawings, and to the letters of reference marked thereon.

In the accompanying drawings—

Figure 1 is a longitudinal vertical section of the lower part of the machine, with a direct lateral view of the upper part of the standards, and the parts connected therewith.

Figure 2 is a detached lateral view of the lower end of one of the swinging arms.

Figure 3 is a detached view of the swinging roller, or upper rubber.

My invention consists chiefly in a peculiar novel construction of elastic rubber, formed by the combination of a fluted roller with rubber rings thereon.

In the construction of my improved washing-machine, a suitable rectangular box, E, is made with two upright standards B.

In the bottom of this box is placed a frame, D, with a series of small rollers, A, grooved as shown in fig. 1.

This frame and series of rollers are made removable, so that one end of the frame may be raised upon the edge of the box, and the rollers thus employed like the common wash-board.

The ends or axes of these rollers, and also those of the upper rubber, fig. 3, are made of wood, instead of iron, as usual, and then a ring, or thimble, S, is put upon such wooden axle to prevent wear, and to allow of easy repair by a new thimble, when out of order from rust or long use.

The upper rubber, fig. 3, consists of a grooved roller, surrounded by a series of rubber rings, F, thus forming a very elastic and efficient rubber, which will not wear or tear the finest fabric.

It will be seen that the water will pass between

these rubber rings, and into the grooves of the roller, as it is pressed from the clothing, by the sudden and ever-varying action of the irregular surface of the roller.

This roller has an elastic bearing, G, fig. 2, which is self-adjusting, by means of a rubber spring, or band, H, which passes through the bearing and fastens the same to the swinging arm I, fig. 1.

The two swinging arms are connected by a cross-bar, K, and supported on a sliding roller, L, which in turn is suspended on the rubber springs M, and also upon the arms of a long wooden spring, N, extending across and some distance beyond the standards B, while the wooden spring is supported only at its middle.

By this arrangement, the arms I, as they swing to and fro, slide freely up and down in the slots of standard B by and thus follow the horizontal series of rollers at the bottom of the box, acting with full force to the ends of the box, while the springs or bands allow the bearing G to yield to extraordinary pressure in passing an unusual obstacle or amount of clothes.

I am aware that rubber rings have been used on a common smooth roller, thus giving equal pressure all around the roller, but I believe it is a great improvement to use a fluted roller, with rubber rings, thus giving different pressure at different points, and producing a rush of water through the clothing.

Having thus fully described my invention,

I claim—

1. The upper rubber, fig. 3, when made of a fluted or irregular roller, covered by rubber rings, substantially as set forth.

2. Also, the above, in combination with the horizontal series of rollers, and the swinging arms I, supported on rubber springs M, and provided with slides G, substantially as set forth.

SEBASTIAN OEDAMER.
